TOILET BOWL VENTILATOR

Henry Jentzer, Chicago, Ill.

Application September 16, 1940, Serial No. 357,049

3 Claims. (Cl. 4—213)

This invention relates to toilet bowl ventilators, and its general object is to provide an automatic apparatus that is rendered active, for dissipating offensive odors from the bowl, when the seat of the latter is occupied, and for that purpose, the apparatus includes a seat operated switch for controlling the motor of a suction fan which is mounted within an air discharge conduit leading to an atmosphere vent, the discharge pipe being in communication with the usual flush pipe of the bowl through the medium of the overflow pipe of the flush tank.

A further object is to provide a toilet bowl ventilating apparatus that can be installed with respect to standard flush tank toilet equipment with minimum change to the structure thereof.

Another object is to provide a toilet bowl ventilating apparatus that is simple in construction, easy to install, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a fragmentary front view, partly in section and illustrates my apparatus installed for use with standard flush tank toilet equipment.

Figure 2 is a fragmentary side elevation illustrating the association of the air discharge conduit with respect to the overflow pipe.

Figure 3 is a sectional view taken through the switch and illustrates the same applied to the seat of the toilet bowl.

Figure 4 is a view of the switch with the cover of the casing thereof removed.

Referring to the drawing in detail, the letter A indicates the toilet bowl, B the seat therefor and C the flush or water discharge pipe leading from the tank D to the bowl, the pipe C having the usual overflow pipe E formed laterally thereon and rising therefrom. The flush pipe C is controlled by the usual float valve F and the float controlled water inlet valve G is equipped with the usual after-fill pipe H to provide the water seal within the bowl. It will be understood that all of this structure is standard equipment and is shown merely to illustrate the relation of my apparatus therewith.

My apparatus in the form shown includes a substantially semi-spherical cup 1 provided with a collar flange 2 sleeved on and fixed to the upper end portion of the overflow pipe E for disposal of the rim of the cup above the upper end thereof, and the cup has mounted therein the outlet end of the pipe H, so that the cup will be retained filled with water at a level flush with the upper end of the pipe E, as will be apparent upon inspection of Figure 1.

Extending into the cup 1 in spaced relation for disposal about and slightly below the upper end of the pipe E, to be sealed by the water in the cup, is the lower end of a double elbow section 3 of an air or odor discharge conduit, the section 3 extending through the rear wall of the tank and has telescopically mounted on the upper end thereof the cylindrical inner portion 4 of a housing for a suction fan. The upper or outlet section 5 of the discharge conduit is telescopically mounted within the cylindrical portion 4 which together with an inner housing member 4' connects the members 3 and 5 in communication with each other, and in order to provide a leak-proof connection between the sections and the portion 4 and inner housing member 4', I provide gaskets 6 surrounding the ends of the inner housing member 4' and bearing against the confronting ends of the sections, as clearly shown in Figure 1.

Mounted and secured vertically within the inner housing member 4' is the suction fan which includes a relatively narrow substantially oval shaped motor 7 having its armature shaft extending through both ends thereof and fixed to the ends of the armature shaft are suction blades 8 for drawing air and consequently offensive odor from the bowl, through the medium of the flush pipe C, overflow pipe E and the elbow section 3 for passage of the air through the inner housing member 4' and the outlet section 5, the latter being connected to an atmosphere vent pipe, not shown, or the section 5 may extend directly to the atmosphere for directing the air thereto, as will be apparent.

The switch for automatically controlling the fan includes an elongated relatively flat rectangular casing 9 provided with a removable cover 10 that may be fixed in closed position by any suitable means, the casing and cover being made from insulating material and the casing is fixed to the underside of the seat B by screws or the like, as best shown in Figure 3. Mounted between its ends in and for disposal between bearings 11 for rocking movement, is a substan-

tially T-shaped contact arm 12 having one end fixed within a knob 13 of rubber or other suitable cushioning material and which extends through an opening in the cover 10 for disposal in abutting relation with the bowl, as clearly shown in Figure 3, the knob being spring pressed for normally urging the same outwardly of the casing, for holding the opposite or cross member end 14 of the arm 12 spaced from a pair of parallel strip contact members 15 that are embedded and fixed within the casing for disposal in the path of the end member 14, for the latter to bridge the contact members 15 to close the circuit to the fan, when the seat is occupied, as will be apparent upon inspection of Figures 1 and 3.

The contact members 15 have one of the ends of conductors 16 connected thereto and their opposite ends are preferably connected to a plug 17 for disposal in a socket outlet member 18 from which extends conductors 19 and 20, the conductor 20 leading to one conductor 21 of a house circuit or which is connected to any suitable source of current, while the conductor 19 extends to the fan motor which has a conductor 22 extending to the other conductor 23 of the house circuit.

From the above description and the disclosure in the drawing, it will be obvious that when the seat is occupied, the circuit to the fan is closed and the latter will remove foul air and offensive odor from the bowl and the surrounding area. It will be further obvious that the housing 24 which includes the cylindrical inner portion 4 tends to deaden the noise of the fan, so that the apparatus is substantially noiseless.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A ventilating apparatus for a flush tank equipped toilet bowl, an overflow pipe for the tank and communicating with the bowl, a pipe for supplying water to the overflow pipe, and said apparatus comprising a water receptacle secured to and surrounding the overflow pipe to extend above the upper end thereof, said receptacle having the outlet end of the water supply pipe extending therein to maintain water within the receptacle at all times, an air conduit including a section having its inlet end mounted

in the receptacle about and below the upper end of the overflow pipe for disposal below the level of the water within the receptacle, a second section for the conduit and communicating with the atmosphere, a housing including a cylindrical portion sleeved on the sections, an inner housing member mounted within the cylindrical portion and the sections, gaskets surrounding the ends of the inner housing member and cooperating therewith and the cylindrical portion to provide a leakproof connection for the sections, a motor driven suction means within the inner housing member, and switch means in circuit with the motor for controlling the latter.

2. A ventilating apparatus for a flush tank equipped toilet bowl, an overflow pipe for the tank and communicating with the bowl, a pipe for supplying water to the overflow pipe, and said apparatus comprising a substantially semi-spherical cup, an annular flange formed on the cup and secured to and surrounding the overflow pipe for disposing the rim of the cup above the upper end of the overflow pipe, said cup having the outlet end of the water supply pipe extending therein to maintain water within the receptacle at all times, an air conduit having its inlet end mounted in the cup about and below the upper end of the overflow pipe for disposal below the level of the water within the receptacle, motor driven suction means within the conduit, and a switch in circuit with the motor for controlling the latter.

3. A ventilating apparatus for a flush tank equipped toilet bowl, an overflow pipe for the tank and communicating with the bowl, a pipe for supplying water to the overflow pipe, and said apparatus comprising a water receptacle secured to and surrounding the overflow pipe to extend above the upper end thereof, said receptacle having the outlet end of the water supply pipe extending therein to maintain water within the receptacle at all times, an air conduit including a double elbow inlet section extending into the tank with its inner end portion depending within the receptacle about and below the upper end of the overflow pipe for disposal below the level of the water within the receptacle, an outlet section communicating with the atmosphere and having one end aligned with the outer end of the inlet section, a housing including a cylindrical portion connecting the aligned ends of the sections together, motor driven suction means within the cylindrical portion, and a switch in circuit with the motor for controlling the latter.

HENRY JENTZER.
